H. C. STALDER,
CHECK HOLDER FOR MINING CARS.
FILED OCT. 10, 1921.

UNITED STATES PATENT OFFICE.

HARRY C. STALDER, OF PORTSMOUTH, OHIO.

CHECK HOLDER FOR MINING CARS.

Application filed October 10, 1921. Serial No. 506,698.

To all whom it may concern:

Be it known that I, HARRY C. STALDER, a citizen of the United States, residing at Portsmouth, in the county of Scioto and 5 State of Ohio, have invented certain new and useful Improvements in Check Holders for Mining Cars; and I do declare the following to be a full, clear, and exact description of the invention, such as will enable others 10 skilled in the art to which it appertains to make and use the same.

This invention relates to an improved check holder for use in connection with mining cars and one object of the invention 15 is to provide a check holder which is so constructed that the checks may be easily placed upon or removed from the holder and at the same time prevented from being accidentally disconnected from the holder.

20 Another object of the invention is to provide a check holder including a check engaging element and a back plate or support having the check carrier connected therewith in an improved manner and securely held in 25 engagement with the back plate.

Another object of the invention is to so 30 construct the back plate that it includes side flanges for engaging the wall of a mine car and further includes a seat for the check carrier, this seat being so formed that its inner face will also engage the face of the mine car and thus prevent the back plate from having any tendency towards tilting and further prevented from being readily 35 bent out of shape or broken loose.

Another object of the invention is to provide a check holder in which the back plate for the check carrier is provided with an extension forming a guard flange which will 40 serve to protect the check carrier and prevent it from being struck by obstructions in the mine while the mining car is in motion.

Another object of the invention is to provide a check holder in which the back plate 45 may be formed of metal and the check carrier formed from a length of wire bent to the desired shape.

Another object of the invention is to so 50 construct this check holder that the fasteners which retain the check carrier in the seat formed in the back plate may also serve as fasteners for passing through the walls of

the mine car and securing the back plate in position upon the car.

This invention is illustrated in the accompanying drawings, wherein:

Figure 1 is a view showing the check holder applied to a portion of a car, the check holder and the portion of the car being shown in elevation.

Figure 2 is a view showing the improved check holder in front elevation.

Figure 3 is a vertical sectional view taken along the line 3—3 of Fig. 2.

Figure 4 is a transverse sectional view 65 taken along the line 4—4 of Fig. 2.

This improved check holder is provided with a back plate 1 which is formed of rather heavy sheet metal and is bent to provide a guard flange 2 which extends from one side 70 of the back plate. The metal at the opposite side and upper and lower ends of the back plate has been bent to provide a rearwardly extending flange 3 which is to engage the outer face of the wall 4 of the mine 75 car 5. When this back plate 1 is formed, the sheet metal blank from which it is formed is punched to provide openings 6 to receive the fastener bolts 7 and the blank is then bent to provide a depression forming 80 a longitudinally extending seat 8 having side extensions 9 extending from its opposite sides adjacent its upper and lower end and extending about the openings 6. From an inspection of Figs. 3 and 4 it will be 85 readily seen that the rear or inner faces of these seats and side extensions, will engage the outer face of the car walls and will thus provide means to assist in bracing and strengthening the plate and also assist in 90 holding the plate against any tendency towards a tilting movement.

The carrier for the check 10 is formed from a strand of resilient wire which is bent to provide a stem 11 and adjacent the upper and lower ends of the stem is bent to provide oppositely extending side arms 12 which are in the form of eyes for fitting into the side extension 9 of the seat 8 and extending about the opening 6 of the back 100 plate. The end portions of the wire are then bent to form the arms 13 and 14, the arm 13 having its free end portion bent inwardly to provide a bill 15 which extends

toward the stem 11 and provides a guard to prevent the check 10 from slipping up onto this arm 13 when the check is being drawn off of the arm or bill 14. This arm 5 or bill 14 engages the lower end of the arm 13 at its juncture with the guard extension 15 and has its free end portion 16 bent so that it extends away from the arm 13 as shown in Fig. 3.

10 When this check holder is in use, the securing bolts are first passed through the eyes 12 of the carrier and are then passed through the opening 6 of the back plate and through openings which will be formed 15 in the wall of the mining car. The securing nuts will then be tightened and the back plate will be securely held in engagement with the car and the carrier securely held in the seat 8 of the back plate. The check 20 can be very easily placed upon the carrier since the perforated portion of the plate can be placed against the arm 13 and the check then moved downwardly so that the bill is passed through the usual opening 25 formed in the check. When it is desired to remove the checks it is simply necessary to draw the checks upwardly and when the checks reach the upper end portion of the bill they will be drawn off of the bill. They 30 cannot, however, slip up upon the arm 13 as the guard extension 15 prevents this. They also cannot accidentally slip off of the carrier as the bill engages the lower end of the arm 13. With this device, the check 35 can be safely carried and cannot accidentally slip off of the carrier and further cannot become lost in case the car should be wrecked. The guard plate 2 prevents the carrier from being struck by any obstruction 40 in the mine which might tend to break the carrier. Although the carrier has been shown connected with the back plate, this back plate may in some cases be omitted and the bolts after being passed through the 45 eyes then pass through the opening formed in the wall of the car, washers being placed upon the bolts if so desired so that these washers will be positioned between the eyes and the outer face of the car wall.

50 I claim:

1. A check holder comprising a back plate, a check carrier extending from said back plate, and a guard for said check carrier extending from said back plate to one side of the check carrier and beyond the outer extremity of the check carrier.

2. A check holder comprising a back plate, and a check carrier extending from said back plate, one portion of the back 60 plate being bent to provide an outstanding flange forming a guard for the check carrier extending from the back plate to one side of the check carrier and extending beyond the outer extremity of the check carrier.

3. A check holder comprising a back plate having a depression in its outer face forming a seat, a check carrier fitting into said seat and having eye portions, and fasteners passing through the eye portions of 70 the check carrier and through the back plate to hold the check carrier in engagement with the back plate and secure the back plate upon a car wall.

4. A check holder comprising a back 75 plate having fastener receiving openings and a seat extending between the openings and having side extensions extending about the openings, a check carrier having a stem portion fitting into the seat and having side 80 arms positioned in the side extensions and extending about the openings, and fasteners passing through the side arms and openings of the plate.

5. The structure of claim 4 having the 85 side extensions adjacent opposite ends of the seat and the check carrier formed of a strand of resilient wire bent intermediate its length to provide a stem portion crimped adjacent its ends to form open side arms 90 fitting into the side extensions of the seat when the stem is positioned in the seat, the end portions of the strand being bent to form upper and lower arms extending towards each other, the upper arm having 95 its end portion bent to extend towards said stem and the end of the lower arm engaging the upper arm at the bend thereof and extending outwardly from the upper arm.

6. A check carrier formed of a strand of 100 resilient wire bent intermediate its length to provide a stem portion crimped to form open side arms, the end portions of the strand being bent to form upper and lower arms extending towards each other, the 105 upper arm extending in diverging relation to the stem and having its end portion bent to extend towards said stem and provide a guard to prevent a check moving upwardly onto the upper arm, the end of lower arm 110 engaging the upper arm at the bend thereof and extending outwardly from the upper arm.

7. A check holder comprising a back plate having rearwardly extending side and 115 end flanges, the plate being provided with fastener receiving openings and pressed from its outer face to provide a seat extending between said openings and having side extensions extending about the openings, a 120 check carrier positioned in the seat and having side arms extending into the side extensions thereof and terminating in eyes positioned about the fastener receiving openings, and fasteners passing through the eyes 125 and fastener receiving openings.

8. A check holder comprising a back plate having rearwardly extending flanges, said back plate being pressed inwardly to form a seat extending longitudinally and 130

having side extensions extending about fastener receiving openings in the back plate, the inner face of the pressed in portion engaging a surface engaged by the rearwardly 5 extending flanges of the back plate, a check carrier fitting into said seat and having side arms fitting into the side extensions of

the seat about the openings in the back plate, and fasteners passing through the side arms and openings of the back plate. 10 In testimony whereof I have hereunto set my hand.

HARRY C. STALDER.
